CLAIM

The ornamental design for a massage device, as shown and described.

DESCRIPTION

1. Massage device

1.1 : Perspective

1.2 : Front

1.3 : Back

1.4 : Left

1.5 : Right

1.6 : Top

1.7 : Bottom

The broken lines shown in the figures are for the purposes of illustrating portions of the massage device which form no part of the claimed design.

A massage device according to the present design has a main body part that performs vibrating operations and a handle part at the base of the main body part; the main body part has a vertical shape suitable for grasping by hand; the tip of the main body part is semi-oval spherical in shape; the surface of the main body part is covered with a soft resin that is water-resistant; in the center of the back of the main body part is provided a circular recess indicating a position of a power switch; the handle part is composed of a pair of curved plate members; the plate members are elastic; the surface of the plate members is covered with a soft resin that is water-resistant together with the main body part.

1 Claim, 7 Drawing Sheets
